(57) **CLAIM**

The ornamental design for an endplate, as shown and described.

DESCRIPTION

FIG. 1 is a perspective view of an endplate, showing our new design;

FIG. 2 is a front perspective view of the endplate;

FIG. 3 is a front view of the endplate;

FIG. 4 is a rear view of the endplate;

FIG. 5 is a top view of the endplate, the bottom view is a mirror image thereof; and,

FIG. 6 is a side view of the endplate, the other side is a mirror image thereof.

The broken lines showing the massage table are for environmental purposes only and form no part of the claimed design.

1 Claim, 3 Drawing Sheets

FIG. 1*FIG. 5*
